SLIDE FASTENER

Filed Feb. 16, 1945

The image contains two technical drawings of gear assemblies. The top drawing, labeled 'Fig. 7.', shows a central gear with a diameter of 15 and a width of 3. It has 16 teeth, with the first tooth at the top. The bottom drawing, labeled 'Fig. 8.', shows a similar gear assembly with a central gear of diameter 15 and width 3, having 16 teeth. It includes a side view of the assembly and a front view showing a hub with a diameter of 4 and a width of 4.5, with a bore diameter of 14.

SLIDE FASTENER

John H. Kohler, Cambridge, Mass., assignor to
 United-Carr Fastener Corporation, Cambridge,
 Mass., a corporation of Massachusetts

Application February 16, 1945, Serial No. 578,240

8 Claims. (Cl. 24—205.16)

1

The present invention relates to slide fasteners and more particularly to slide fasteners of the type having complementary interlocking coil fastener elements, each of which is suitably attached to a stringer, the coils being capable of being interlocked and disengaged by the action of a slider movable longitudinally thereon.

Slide fasteners of the type having interlocking coil fastener elements are well known. They ordinarily comprise a pair of stringers of suitable material, and a pair of complementary interlocking helical coils, one of which is attachable to an edge of each stringer. The coils are embraced by a slider which moves them into and out of interlocking meshed relationship.

The stringers of such slide fasteners frequently are flexible members, for example strips of woven material, and are frequently attached to flexible members, for example parts of clothing and the like. If the part of the garment or stringer above the slide is bent outwardly, the spacings between the convolutions of the coils are apt to be disposed parallel to and in alignment with the side flanges of the slider. In such condition, movement of the slider in a direction to close the coils, often results in the retaining or side flanges of the slider being pulled through the aligned space between adjacent convolutions of one coil resulting in disengagement of the slider from that particular coil. The fastener is thus rendered inoperative and useless.

The present invention has for its object generally to improve the construction of slide fasteners and more particularly to provide an improved construction in which the slider is prevented from being pulled through the spaces between the coils.

A further object of the invention is the provision of an improved coil type slide fastener in which each coil is securely attached to its carrying stringer so as to maintain the coil in position with its axis disposed in the plane of the web of the stringer tape.

A still further object of the invention is the provision of an improved coil type slide fastener in which each coil is attached to its carrying stringer by means embracing each convolution of the coil at a plurality of circumferentially spaced places.

Another object of the invention is to improve the construction of coil-attached stringer tapes for use in slide fastener installations of the interlocking coil type.

In the drawings—

Fig. 1 is a front elevation of a portion of a

2

slide fastener installation illustrating one embodiment of the invention;

Fig. 2 is an enlarged vertical sectional view of a portion of a slide fastener according to the invention, the stringer tapes and attached coils being shown in elevation;

Fig. 3 is an enlarged detail horizontal sectional view of the fastener illustrated in Fig. 1 as taken on the line 3—3 of Fig. 1;

Fig. 4 is an enlarged horizontal sectional view similar to Fig. 3 of a modified construction;

Fig. 5 is an enlarged horizontal sectional view similar to Fig. 3, of a further modified form of the invention;

Fig. 6 is an enlarged horizontal sectional view, similar to Fig. 3 of a still further modified form of the invention; and

Figs. 7 and 8 are enlarged horizontal sectional views of further modified forms of the invention.

Referring to the drawings, the fastener may be of any approved type of slider-operated coil fastener comprising opposed stringers 1 and 2, each having secured to an edge thereof, one coil 3 or 4 of a pair of cooperating co-mating interlocking coils adapted to be embraced by a slider 5 of usual construction for engaging and disengaging the coils by movement of the slider longitudinally therealong.

The slider 5, of conventional form, comprises generally similar wings or plate portions 6, each provided with marginal side flanges 7 and connected near their upper edges by a neck or wedge 8 which maintains them in fixed spaced relation, and which cooperates with the marginal side flanges 7 to form a substantially V-shaped channel or passage for progressively guiding the coils 3 and 4 into and out of interlocking relationship. The inner marginal edges 9 of the side flanges are spaced apart sufficiently to slidably receive, without wear, the stringers 1 and 2.

According to the invention, at least one form of the stringers is provided with means positioned between a marginal side flange on the slider and an adjacent coil section, providing a substantially continuous guide for the slider to facilitate slidability of the slider along the stringer as well as to prevent disengagement of the slider from a coil and a stringer, even though a spacing between certain convolutions of a coil be disposed in substantial alignment with the marginal side flanges 7 of the slider during closing movement of the slider.

In the form of invention illustrated in Figs. 1 and 2, the stringers 1 and 2 may be continuous lengths of suitable flexible material, for example

a woven fabric strip, along the adjacent edges of which are lengths of coils adapted to be mated together into interlocking relationship. Preferably, these coils are formed from filaments of non-circular cross section and may be secured to the edges of the stringers by suitable loops 18, as for example by separate stitches embracing each convolution of the coil and connecting them to the edge of the stringer.

In the form of the invention shown in Figs. 1 and 2 a plurality of slider guiding strips 11-12 are provided for each stringer, and preferably these are positioned along opposite faces of the stringers adjacent the coil-attached edge to provide substantially continuous guides between the outer peripheral faces of the coils and the inwardly extending marginal flanges 7 of the slider. The guides are of such dimensions that the combined thickness of the stringers 1 or 2 and associated guides 11 or 12 will be substantially greater than the spacing between the marginal free edges 9 of the slider flanges 7 on opposite sides of the stringer.

The guides 11 and 12 of Figs. 1 and 2 may be of any suitable material, for example heavy cord or beads of flexible material, such as leather or woven, knitted, or braided fabric or the like and may be secured to the stringer by any suitable means such as stitching 13. These guides or beads may, if desired, also be secured to the coils 3 or 4 on the respective stringers, as by stitching or loops 14 embracing each convolution, and thus secure the coils to the stringer against twisting. This insures that the axis of the coil is parallel to and in the plane of the stringer tape and permits easier operation of the slider because the coils 3 and 4 are more readily moved into and out of co-mating interlocking relationship.

It is not absolutely necessary that the guides or beads 11-12 be secured on opposite sides of the stringer tapes as illustrated in Fig. 3. Optionally, guides or beads 11a-12a may be attached to only one side of the tapes as shown in Fig. 4, providing the combined thickness of the beads 11a-12a and the stringer tapes 1a and 2a will be substantially greater than the spacing between the marginal free edges 9 of the slider flanges 7 on opposite sides of the stringer tape. The coils 3 and 4 may be secured to their respective stringers 1a and 2a and beads 11a and 12a in the manner disclosed in Fig. 4, in which case there are two spaced loops 10a and 14a surrounding each convolution of the coils for securing the coils parallel to and in the plane of the stringer.

In a modified form of the invention shown in Fig. 5, the interlocking fastener coils 3-4 may be formed of an organic plastic material such as solid polymers of styrene, vinyl chloride, vinylidene, chloride, methyl methacrylate etc. or resinous copolymers of such compounds with other unsaturated organic compounds. These may include any of the well known synthetic thermoplastic compounds possessing the properties of being drawable into a filament sufficiently stiff and elastic to retain its shape after being formed but sufficiently flexible so that it may be readily bent without breaking.

These organic thermoplastic coils may be attached to the stringers 1 and 2 in any suitable manner, as above described or by employing similar organic thermoplastic guides or beads 21 or 22 on one or both sides of each stringer. These organic thermoplastic guides may be attached to the stringer tapes in any suitable manner, for example as by stitching 23 as is illustrated with

respect to the guide strip 21 of Fig. 4. Alternatively, the plastic guide strips 21-22 may be heated to cause the plastic metal to flow through the fabric stringer, and become fused together as is illustrated at 23a with respect to the guide 22 of Fig. 5.

Similarly the plastic guide strips 21-22 may be united or fused to the outer peripheral faces of the coil convolutions by heating so that the coils will be accurately attached to the stringer tape and maintained in a position parallel to and in the plane thereof. As will be apparent, the combined thickness of the stringers 1 or 2 with the associated guide strip 21 or 22 will be substantially greater than the spacing between the opposed free edges 9 of the marginal side flanges 7 of the slider 6, so as to prevent the slider from becoming disengaged from the coils.

As is illustrated in Fig. 6, the stringer tapes 31-32 are preferably woven tapes employing a plurality of small warp threads 33 and one or two large diameter warp threads 34 of suitable diameter to form a slider-retaining head for the stringer. The weft threads 35 are woven around the warp threads 33-34 in such a manner as to form a T-shaped tape having large diameter guides at the head of the T on opposite sides of the web and formed by the large diameter threads or cords 34. The coils 3 and 4 may be connected to the respective tapes 31-32 by stitches or loops 36 from each large diameter thread 34 and embracing successive convolutions of the coils 3 and 4 at spaced circumferential points to securely hold the coils against their respective tapes with the axis thereof in the plane of the web of the tapes.

In Figs. 7 and 8 there are illustrated further modified forms of the invention wherein woven stringer tapes 41-42 may be woven directly to the coils 3-4 either by a single loop 43 of the weft thread 45 around the coil, as in Fig. 7 or by a plurality of loops 43-44 of the weft thread 45 around each coil. In such cases the guides may be in the form of beads 46 stitched preferably to both sides of the woven stringer tapes 41-42 by stitching 47.

From the above it will be apparent that the invention provides a novel construction of coil-attached stringer tape provided with a continuous guide for a slider which will prevent the slider from becoming disengaged from the coil intermediate its ends. Furthermore, the provision of the beads on the tapes affords a guide for the slider facilitating easier sliding movement thereof and additionally provides a coil-attaching edge of considerable width permitting a plurality of coil-attaching means for each convolution of the coil to hold the coil in proper position relative to the stringer tape.

It is to be understood that the invention is not to be restricted to the details of construction as shown and described, as the scope of the invention is best defined by the appended claims.

I claim:

1. A slide fastener comprising a pair of stringer tapes, a substantially continuous bead strip secured to one face of each tape adjacent one edge thereof, a fastener coil for each tape including spaced successive convolutions, and means connecting each of said successive convolutions to said one edge of said tape and said bead strip at a plurality of circumferentially spaced points to attach the coil securely to said tape.

2. A slide fastener comprising a pair of stringer tapes, a substantially continuous bead strip se-

cured to one face of each tape adjacent one edge thereof, a fastener coil for each tape including spaced successive convolutions, and loop means connecting each of said successive convolutions to said one edge of said tape and said bead strip at a plurality of circumferentially spaced points on each of said convolutions to attach the coil securely to said tape.

3. A slide fastener comprising a pair of stringer tapes, substantially continuous bead strips secured to opposite faces of each tape adjacent one edge thereof, a fastener coil for each tape including spaced successive convolutions, and means connecting each of said successive convolutions to said one edge of said tape and said bead strip at a plurality of circumferentially spaced points on each of said convolutions to attach the coil securely to said tape.

4. A slide fastener comprising a pair of stringer tapes, substantially continuous bead strips secured to opposite faces of each tape adjacent one edge thereof, a fastener coil for each tape including spaced successive convolutions, and loop means connecting each of said successive convolutions to said one edge of said tape and said bead strip at a plurality of circumferentially spaced points on each of said convolutions to attach the coil securely to said tape.

5. A slide fastener comprising a pair of woven stringer tapes, a substantially continuous bead strip secured to one face of each tape adjacent one edge thereof, said bead strip comprising an enlarged warp thread woven into said tape on said face at said edge, a fastener coil for each tape including spaced successive convolutions, and loop means connecting each of said successive convolutions to said one edge of said tape and said bead strip at a plurality of circumferentially spaced points on each of said convolutions to attach the coil securely to said tape.

6. A slide fastener comprising a pair of stringer tapes, substantially continuous bead strips secured to opposite faces of each tape adjacent an

edge thereof, said bead strips comprising enlarged warp threads woven into said tape on said opposite faces at said edge, a fastener coil for each tape including spaced successive convolutions, and loop means connecting each of said successive convolutions to said one edge of said tape and said bead strips at a plurality of circumferentially spaced points on each of said convolutions to attach the coil securely to said tape.

10 7. A slide fastener comprising a pair of stringer tapes, substantially continuous bead strips secured to opposite faces of each tape adjacent one edge thereof, and a fastener coil for each tape including spaced successive convolutions, each convolution being connected to said one edge of

15 said tape and integrally joined to said bead strips at a plurality of circumferentially spaced points on each of said convolutions to attach said coil to said tape.

20 8. A slide fastener element comprising a stringer tape, a substantially continuous bead strip secured to one face of said tape adjacent one edge thereof, a fastener coil including spaced successive convolutions, and means connecting each of said spaced successive convolutions to said one edge and said bead strip at a plurality of circumferentially spaced points on each of said convolutions to attach the coil securely to said tape.

25 30 9. A slide fastener element comprising a stringer tape, a substantially continuous bead strip secured to one face of said tape adjacent one edge thereof, a fastener coil including spaced successive convolutions, and means connecting each of said spaced successive convolutions to said one edge and said bead strip at a plurality of circumferentially spaced points on each of said convolutions to attach the coil securely to said tape.
